(57) **CLAIM**

The ornamental design for the cabinet, as shown and described.

DESCRIPTION

FIG. 1 is a perspective view of the cabinet comprising our new design;

FIG. 2 is a top plan view thereof;

FIG. 3 is a front elevational view thereof;

FIG. 4 is a left side elevational view thereof, the right side elevational view being a mirror image thereof; and,
FIG. 5 is a front elevational view of a second embodiment of the cabinet, shown in FIG. 1, the sole difference residing in the joining together of two cabinets.

The broken line showing of an additional cabinet in FIG. 5 is for illustrative purposes only and forms no part of the claimed design.

The bottom and rear form no part of the claimed design.
